UNITED STATES PATENT OFFICE

2,639,030

REFILL UNIT FOR BLADE MAGAZINES

Joseph Muros, Cambridge, Mass., assignor to The Gillette Company, a corporation of Delaware

Application February 25, 1947, Serial No. 730,841

4 Claims. (Cl. 206—16)

1

This invention comprises a refill unit for use in connection with magazines for safety razor blades or the like, that is to say, a unit comprising a blade or a stack of blades assembled and packaged so that it may be distributed in commerce as a sales article and inserted bodily in a magazine from which the blade or the individual blades of the stack are to be subsequently ejected or delivered as desired by the user.

One manner of distributing safety razor blades to the public is to package them in a complete magazine which may include inner and outer shells provided with a blade exit opening and a spring acting to position a selected blade in alignment with the opening in the magazine. It is not usually practicable to return such magazines for refilling, and they are too expensive to be thrown away after the charge of blades has been exhausted. The present invention contemplates a unit that may be conveniently produced by the blade manufacturer, which will adequately safeguard a blade or a stack of blades in storage, shipment and sales handling, and which may be readily inserted in and form a part of the ultimate magazine assembly and construction.

Going more into detail, the unit of my invention comprises a rectangular shell or frame having therein blade-locating means, a stack of slotted blades held thereby with their sharpened edges out of contact with the walls of the unit, and a retaining element removably secured to the shell or frame and having a portion shaped to engage the blade stack and hold it against removal. Preferably and as herein shown, the retaining element is arranged to be disengaged from the refill unit simultaneously with the introduction of the unit into the casing of the magazine of which it is to become a part.

These and other features of the invention will be best understood and appreciated from the following description of a preferred embodiment thereof selected for purposes of illustration and shown in the accompanying drawings in which:

Figure 1 is a view in perspective on an enlarged scale of the refill unit.

Figure 2 is a view in cross-section on line 2—2 of Figure 1.

Figure 3 is a view of the unit and its enclosing magazine in longitudinal section.

Figure 4 is a view in perspective showing the unit partially inserted in the magazine with which it is to be associated.

Figure 5 is a view in longitudinal section of the partially charged magazine; and

Figure 6 is a view in perspective of the retaining member or keeper.

2

The refill unit selected for purposes of illustration is constructed and arranged to handle double-edged slotted blades of a well-known commercial type, and it will be understood that the illustrated construction may be modified within the scope of the invention to accommodate blades of other types.

The refill unit as illustrated in Figs. 1-2, comprises an open rectangular shell having a bottom 10, side walls 11 and 12, a notched rear wall 13 and a front wall 14. The bottom 10 is provided with two long parallel slots 15 and 16, shaped to receive with clearance a forked spring which is part of the magazine construction to be presently described. The slots 15 and 16 extend forwardly from adjacent to the rear wall of the unit to and up into its front wall 14 as shown in Fig. 1. The front wall 14 is somewhat shorter than the other walls of the unit, terminating so as to provide the lower edge of an exit opening when the unit is assembled in the magazine. The wall 14 is also provided at its upper edge with a pair of forwardly-extending ears or lugs 17.

A blade-locating projection in the shape of a rib or bar 18 rises from the bottom 10 of the unit being disposed in the median axis thereof and having a rear beveled end 19. A spring clip 20 is secured to the notched rear wall 13 of the unit by a hollow rivet 21. The clip extends downwardly from the wall 13 through a goose-neck shank and then forwardly beneath it in a flat portion provided with a circular aperture 22 and is designed to interlock with the magazine preferably by engaging the projecting end of a rivet 36 in the bottom of the magazine casing.

In Figs. 1-3, the refill unit is shown as loaded with a stack of ten or twelve blades 23, each having a central longitudinal slot to receive the blade-locating bar 18 and being notched in each of its corners so that it presents elongated unsharpened end portions. The blade slots include local enlargements shaped to engage blade-positioning projections of the razors in which the blades are to be used. The blades are held by the bar 18 with their sharp longitudinal edges safely out of contact with the walls of the unit and it will be understood that the blades may be delivered to the unit by automatic machinery without any danger of contact with or damage to the exceedingly keen and therefore delicate edges produced under the most favorable manufacturing condition.

After the stack has been assembled in the shell upon the bar 18, it is held in that position by a keeper or retaining clip 24. This is formed, as best shown in Figure 6, with a bridge, side

walls and inturned bottom flanges which fit about the shell of the unit in such manner that the clip may slide longitudinally upon it. The bridge portion of the keeper is provided with a pair of downwardly-extending ribs 25. These bear frictionally upon the uppermost blade 23 in the blade stack, holding the blades down against the bottom 10 of the shell and positively preventing them from lifting above the bar 18 so that they may not be disengaged. The wall 11 of the shell is provided with a hole 27 and one wall of the clip is provided with a pressed in boss 26 which is adapted to snap into the hole 27 and frictionally hold the keeper in its operative position on the shell as shown in Fig. 1. It will be seen that the ribs 25 of the keeper engage the blade stack over a substantial area on both sides of the bar 18. Accordingly as long as the keeper 24 occupies its operative position the blades are safely retained in the position shown. On the other hand when the keeper is forcibly freed from its locking engagement, the keeper may be moved longitudinally and entirely disengaged from the shell. In this disengaging movement the ribs 25 of the keeper pass freely through the notches or apertures 25a provided for that purpose in the rear wall 13 of the shell. A refill unit with its charge of blades may be now wrapped and distributed to the users through the ordinary channels of commerce. It is adapted in its illustrated construction to be used in combination with a blade magazine of the type shown in Figs. 3, 4 and 5 and the magazine, completed by the insertion of the refill unit, may be used to supply razor blades one at a time to a safety razor, for example to a safety razor such as that shown in U. S. Letters Patent No. 2,392,432, Testi, dated January 8, 1946.

The illustrated magazine comprises a rectangular casing or shell having a bottom 30, side walls 31 and 32, and inturned top flanges 33 of such dimensions as to receive telescopically and frictionally the shell of the refill unit. The bottom 30 is extended forwardly and shaped as a flanged trough 34 to receive and position one end of a safety razor for receiving a blade from the magazine. A forked spring 35 is secured to the inner face of the bottom 30 of the magazine by a hollow rivet 36 and this spring serves in the loaded magazine to urge the blade stack always upwardly against the flanges 33, thereby maintaining the uppermost blade in the stack in alignment with the exit opening of the magazine which is to be formed above the front wall 14 and the ears 17 of the refill unit.

The casing is also equipped with a feed slide comprising a corrugated head 37 and a thin elongated plate 38 provided with a central rib 39 arranged to travel in a space between the inturned ribs 33 of the magazine shell. The plate 38 is provided near the head 37 with a pair of diverging slots 41, one being shown in Fig. 4. These slots have offset edges arranged to engage the two rear corners of the blade uppermost in the blade stack. The stroke of the feed slide is limited by upturned ears 40 located at the forward end of the flanges 33 and similar ears 41 located at the rear end of these flanges.

When the refill unit is to be inserted in the casing of the magazine the forward end of the unit is telescopically entered within the rear end of the magazine shell and the unit is pushed forwardly. A preliminary position of the unit is indicated in Fig. 5 and the final position of the unit in the magazine casing is shown in Fig. 3. It will be seen that as the refill unit is advanced

the keeper encounters the rear end of the magazine casing, as shown in Fig. 4, and is held in stationary position while the unit is advanced within it by pressure of the user against its rear end. The keeper 24 is finally disengaged from the rear end of the unit having remained at rest while the shell of the refill unit travels entirely through it. The flanges of the keeper are cut away, as shown in Fig. 6 so that the thumb of the operator may follow the rear wall of the refill unit completely through the clip as suggested in Fig. 3. The advancing movement of the unit continues until the hole 22 in the spring clip 20 is brought into registration with the rivet 36 in the bottom of the magazine. When this occurs, the rivet 36 snaps into the hole 22 in the clip and the refill unit is automatically locked in its proper position within the shell of the magazine. Meanwhile the slots 15 and 16 have been moved into registration with the forks of the spring 35. The spring accordingly passes upwardly through the bottom 10 of the refill unit, engaging and lifting the blade-stack into contact with the flanges 33 of the magazine shell and aligning the uppermost blade of the stack in position to be engaged by the feed slide 37-38 and ejected when the latter is advanced. The magazine thus completed may be used until the charge of razor blades is exhausted, whereupon the spring clip 20 may be broken or disengaged from the rivet 36 and the empty unit withdrawn and discarded. Subsequently a new refill unit may be inserted and the magazine again placed in commission for use. It will be understood that in bending or breaking the clip 20, as is necessary to permit removal of the empty refill unit from the magazine, the device as a whole will be damaged so that it cannot be used again.

Having thus disclosed my invention and described in detail an illustrative embodiment thereof, I claim as new and desire to secure by U. S. Letters Patent:

1. In a blade magazine having an outer casing of rectangular cross section, a refill unit for safety razor blades comprising an elongated shell of smaller cross section than the outer casing having a bottom, front and rear walls, the bottom having longitudinal spring-receiving slots, the shell being partially inserted in and having a sliding fit with the casing, and a hold-down keeper slideable on the shell and having downwardly-extending ribs therein and an end portion engaged with the magazine casing, the said rear wall of the shell being notched to permit the passage there-through of the ribs of the keeper.

2. A refill unit for safety razor blades comprising an elongated shell having a bottom, front and rear walls, an internal rib upstanding from said bottom wall, a stack of slotted blades threaded on said rib, a hold-down keeper slideable on said shell and having downwardly-extending ribs normally engaging the blade stack, the said rear wall of said shell being apertured to permit the passage there-through of the ribs of the keeper.

3. A blade magazine having an outer casing of rectangular cross section, a refill unit for safety razor blades comprising an elongated shell of smaller cross section than the outer casing having a bottom, front and rear walls, the shell being partially inserted in and having a sliding fit with the casing, and a hold-down keeper slideable on the shell and having downwardly-extending ribs therein and an end portion engaged with the

magazine casing, the said rear wall of the shell being notched to permit the passage therethrough of the ribs of the keeper.

4. A blade magazine having an outer casing of rectangular cross section, a refill unit for safety razor blades comprising an elongated shell of smaller cross section than the outer casing having a bottom, front and rear walls, the bottom having an upstanding internal rib, a stack of slotted blades threaded on the rib, the shell being partially inserted in and having a sliding fit with the casing, and a hold-down keeper slidable on the shell and having downwardly-extending ribs therein normally engaging the blade stack and an end portion engaged with the magazine, the said rear wall of the shell being notched to permit the passage therethrough of the ribs of the keeper.

JOSEPH MUROS.
